UNITED STATES PATENT OFFICE

WILLIAM H. SOMMER, OF PEORIA, ILLINOIS

ARTICLE OF MANUFACTURE

Substitute for application Serial No. 241,255, filed December 19, 1927. This application filed April 4, 1929. Serial No. 352,593.

This invention has reference to an article of manufacture, such as may be employed as a "skimmer" in the art of galvanizing wire.

"Skimmer" as the term is employed in the art of galvanizing wire has reference to means or elements used in association with a galvanizing unit to prevent the formation of sleeves on the wires, as the coated wires leave the bath, as distinguished from "wipers" so called. The latter are used to thin the zinc coat on the wires, whereas, "skimmers" leave a comparatively heavy coat, which is smooth, and when such "skimmers" are supported whereby they are adapted to align themselves to the axial movement of the wires, surface irregularities in the zinc coating are prevented.

It is the principal object of the invention to provide such an article from a strip or piece of wire bent back on itself and flattening the ends to provide adjacently lying portions, the meeting edges of which are correspondingly notched, which unite to provide a wire opening for the passage therethru of a coated wire. These notches may be of a size to accommodate whatever gauge of coated wire is desired. At the ends of the flattened portions their meeting edges are beveled or diverge, or are spread apart to facilitate in the insertion of a wire therebetween and into the notches; the article having sufficient spring to permit such insertion of the coated wire and to return to guiding position when such coated wire is in position.

That the invention may be more fully understood, reference is had to the accompanying drawings forming part of this description, illustrating a preferred embodiment of the invention, in which:

Fig. 1 is a perspective view of an article embodying my invention, and

Fig. 2 is a perspective view of the guiding end of the article and showing a form of support for the flattened end of the article, dotted lines showing a wire being guided thru and by the article.

Like characters of reference denote corresponding parts thruout the figures.

The article is preferably made from a piece or strip of iron or steel wire 1, of suitable

length bent back on itself at 2 and having its terminals flattened as at 3, for a suitable length and their meeting edges 4 lying next adjacent or normally in juxtaposition, as shown, and at 5 these meeting edges are beveled, diverge or are spread apart to provide a mouth or throat 6. The adjacent edges 4 of the flattened portions, at a suitable point are provided with corresponding and complementary notches 7 which unite to provide an opening, of suitable diameter to admit of a coated wire passing therethru, as the coated wire is drawn from a coating bath, not shown. The wire constituting the article has a certain amount of spring, due to its formation, so that by exerting a little pressure or force a coated wire, such for instance as A, Fig. 2, may be inserted thru the mouth or throat 6 and caused to pass in between the adjacent edges 4 and become seated in the opening formed by the notches 7 and have movement therein transversely of the flattened ends of the article. On the seating of the coated wire, the terminals will assume the position shown in the figures.

Altho not shown, the article may be supported from the end 2 so that the flattened ends may align themselves to the axial movement of the coated wire A, and the flattened ends may rest and have lateral movement on a suitable support B.

This application is a continuation and substitute for the application filed by me Dec. 19, 1927, bearing Serial No. 241,255.

What I claim is:

1. An article of manufacture for use as a "skimmer" in the coating of wire comprising a resilient member bent back on itself and having terminals, the adjacent meeting portions of which have complementary notches uniting to provide a wire guiding opening.

2. An article of manufacture for use as a "skimmer" in the coating of wire comprising a resilient member bent back on itself and having flattened terminals, the adjacent edges of which have complementary notches uniting to provide a wire guiding opening and the end of said flattened portions being spread apart to provide a throat therebetween.

3. An article of manufacture for use as a "skimmer" in the coating of wire comprising a wire bent back on itself and having its ends flattened with adjacent meeting edges having complementary notches uniting to provide an opening.
4. An article of manufacture for use as a "skimmer" in the coating of wire comprising a wire bent back on itself and having its ends flattened with adjacent meeting edges having complementary notches uniting to provide an opening, and the ends of such flattened portions being spread apart to provide a throat therebetween.

15 In witness whereof, I have signed my name this 30th day of March, 1929.

WILLIAM H. SOMMER.
